(57) **CLAIM**

The ornamental design for a tumbler bottle, as shown and described.

DESCRIPTION

FIG. 1 is a right side view of a tumbler bottle showing my new design.

FIG. 2 is a front view thereof;

FIG. 3 is a left side view thereof;

FIG. 4 is a rear view thereof;

FIG. 5 is a top view thereof;

FIG. 6 is a perspective view thereof;

FIG. 7 is a perspective exploded view thereof; and,

FIG. 8 is a cross-sectional view taken along line 8-8 of FIG. 4.

The broken lines in the drawings depict portions of the tumbler bottle that form no part of the claimed design.
